UNITED STATES PATENT AND TRADEMARK OFFICE
CERTIFICATE OF CORRECTION

PATENT NO. : Des. 374,258
DATED : October 1, 1996
INVENTOR(S) : Sten Schmidt and Kurt Jensen

It is certified that error appears in the above-identified patent and that said Letters Patent is hereby corrected as shown below:

On the face of the patent, between item [73] and [**] Term, this patent has been terminally disclaimed to expire with Patent No. Des. 368,497 which expires on April 2, 2010, and therefore the present patent should read as follows:

[*] Notice: The portion of the term of this patent subsequent to Apr. 2, 2010, has been disclaimed.

Signed and Sealed this
Twenty-sixth Day of August, 1997

Attest:

BRUCE LEHMAN

Attesting Officer

Commissioner of Patents and Trademarks
